UNITED STATES PATENT OFFICE

HENRY THOMAS, OF BARKING, ENGLAND, ASSIGNOR TO U. S. SLICING MACHINE COMPANY, OF LA PORTE, INDIANA, A CORPORATION OF INDIANA

END GUARD FOR SLICING MACHINES

Application filed December 11, 1929, Serial No. 413,150, and in Great Britain April 24, 1929.

The present invention relates to slicing machines and particularly that type which includes a carriage adapted to carry the substance to be sliced recurrently past a slicing knife. Such machines generally are installed for use upon a supporting structure such as a shop counter. As such machines are usually designed so that the carriage moves beyond the base, customers are apt to be struck by the moving carriage or mechanism associated therewith especially in the case where the machine overhangs the structure supporting it.

One object of this invention, therefore, is to provide means for preventing customers from being struck by the moving parts of such a machine.

Another object of this invention is to provide an end guard attached to the slicing machine so as to be positioned beyond the end of the travel of the slicing machine carriage and its associated parts.

Another object of this invention is to provide means for preventing endwise bodily movement of the slicing machine base, at least in one direction, as it is well-known that such machines generally have a tendency to creep in a direction towards the operator's position unless means is provided for preventing such movement. This creeping is due to the fact that the movement of the carriage on the base re-acts to move the base in one direction more than the other. This has been found true in actual practice and this is a disadvantage in that it necessitates occasionally shifting the machine bodily back to its original position.

Another object of this invention is the provision of a means for preventing bodily movement of the slicing machine by a stop member which does not have to be fastened to the supporting structure. This is an advantage in view of the fact that such a stop member can be readily used with a slicing machine adapted to be placed on counters or other supporting structures, the appearance of which would be marred by the use of permanent fastening means or stop members fastened thereto, or by the marks left thereby after the stop members were removed.

A further object of this invention is the provision of a guard which not only protects the customer from being struck but also permits the customer to see the reciprocating carriage and the substance supported thereon. More specifically, my invention contemplates using a guard constructed of glass or other transparent material although it will be understood that metal guards or any other type of opaque guard may be used, if desired.

Another object of this invention is the provision of a guard which can be readily removed for the purpose of cleaning or replacing the same.

In the drawings:—

Fig. 1 is an end elevation of a device embodying my invention;

Fig. 2 is a fragmentary side elevation of the end of the slicing machine to which the guard is attached, showing the manner in which the carriage overhangs the base at the end of the base;

Fig. 3 is a plan view of the device shown in Fig. 2;

Fig. 4 is a modification partly in section of the device shown in Fig. 2;

Fig. 5 shows a modification of the devices disclosed in Figs. 1 to 4, inclusive;

Fig. 6 is a view in side elevation of the device shown in Fig. 5; and

Fig. 7 is a plan view of the device shown in Figs. 5 and 6 with the base of the slicing machine illustrated in dotted lines.

Referring first to Figs. 1 to 4, inclusive, 1 represents the base of a slicing machine embodying my invention and 2 represents the carriage movably supported thereon by means of the rollers 3 and 4 engaging suitable guides 5 and 6 on the slicing machine base, the carriage 2 being reciprocated in the usual manner by means of a hand-wheel (not shown), said hand-wheel being adapted to rotate the crank 7 and impart movement to the connecting rod 8 in such a manner that the carriage is reciprocated along the guides 5 and 6. As will be apparent from an inspection of Fig. 2, the carriage is adapted to extend over one end of the base, in one of its limiting positions, and customers are apt to be struck by the carriage and its as-

sociated mechanism if no means are provided to prevent this. The carriage 2 is provided with the usual feeding mechanism 9 arranged on the end of the reciprocating carriage adjacent the customer's position.

In order to prevent the customer from being struck by the carriage or its associated mechanism, I provide a suitable guard arranged beyond the limit of the travel of the carriage and mechanism supported thereby. This guard comprises a pair of brackets 10 and 11 fastened by suitable screws 12 and 13 to the base of the machine and each of these brackets has a groove 14 adapted to receive one edge of the glass guard plate 15. The grooves 14 have rollers 16 rotatably mounted therein at the lower ends thereof, as best illustrated in Figs. 1 and 2. These rollers 16 are adapted to support the glass guard plate 15 arranged in the grooves 14, the glass guard plate being readily removable from the grooves for the purpose of cleaning or replacing the same. It is not necessary that the rollers 16 be rotatably mounted but, by rotatably mounting these rollers in the grooves 14, different supporting surfaces of the rollers may be presented to the glass guard plate. Preferably, these rollers 16 are made of resilient material, such as rubber, leather, or the like, and are fastened in grooves by means of the screws 17 so that the same can be replaced when worn out.

The device shown in Fig. 4 has suitable brackets such as the brackets 10 and 11, shown in Figs. 1 to 3, inclusive, for supporting the glass guard plate 18. One of these brackets 19 is shown in Fig. 4 and corresponds to the bracket 11, shown in Figs. 1 to 3, inclusive, it being understood that the bracket, such as the bracket 10 shown in Figs. 1 to 3, inclusive, is used to support the other end of the glass guard plate 18. However, in the modification shown in Fig. 4, each of the brackets, or at least one of the brackets, is provided with a depending portion such as the portion 20 on the bracket 19. Each of these depending portions is provided with an opening which slidably receives the member 21 having a hook-shaped portion 22 adapted to extend over the edge of the counter 23. This member 21 is locked in position by means of the set screw 24. Since the slicing machine base has a tendency to move to the left, as viewed in Fig. 4, the hook-shaped portion 22 extending over the edge of the counter 23 will resist this movement and prevent the table from having bodily movement in a direction toward the operator's position. Means similar to the members 21 may be provided at the other end of the machine to prevent movement of the base in the opposite direction, if the base has a tendency to move to the right instead of to the left. It will

be noted that by loosening the set screw 24, the member 21 can be adjusted to various positions.

Referring now to the modification shown in Figs. 5 to 7, inclusive, it will be noted that, in this embodiment of the invention, the guard plate is not directly fastened to the base but is constrained to occupy a definite fixed position relative thereto. The base 1' of the machine shown in Figs. 5 to 7, inclusive, has depending legs 25 provided with the feet 26. The feet 26 are made of resilient material preferably rubber, and, as best illustrated in Figs. 5 and 6, have oppositely extending conical portions, one of which is adapted to rest in a recess of the legs 25, the other of which is adapted to rest in a suitable recess in the adjacent bracket 27 or 28.

Each of the brackets 27 and 28 has an outwardly extending finger portion 29 having a substantially V-shaped groove 30 therein adapted to receive the adjacent depending flanged portion 31 of the base 1'. Thus, it will be seen that by the means just described, the brackets 27 and 28 are constrained to move with the base member 1' as long as the base member is operatively connected by means of the feet 26 and the flange 31 engaging the groove 30 in the finger 29. However, it will be readily seen that, by merely raising the base member, the same will become disengaged from the bracket members.

Each of the brackets 27 and 28 carry upstanding identical auxiliary brackets 32. As is best illustrated in Fig. 6, each of these brackets 32 carries a pair of clamping members 33 and 33' arranged in opposed spaced relation to each other, each of the clamping members 33 and 33' being provided with suitable packing strips 34 for engaging the glass guard plate 35 which is interposed between the opposed faces of the packing strips 34. The packing strips 34 may be made of rubber or any other material suitable for this purpose.

The clamping member 33 is preferably formed integral with or rigidly attached to the auxiliary bracket 32 and the clamping member 33' is a separate part which is connected to the clamping member 33 by means of the bolt 36 which extends through an unthreaded opening in the clamping member 33' and a threaded opening in the clamping member 33. By tightening the bolt 36 by means of the winged head thereon, the clamping members 33 and 33' are drawn against the opposite sides of the glass guard plate 35. Each of the clamping members 33' is provided with a laterally extending portion 37 adapted to engage the clamping member 33 and hold the clamping members 33' and 33 in spaced relation to each other adjacent their lower ends, the upper ends thereof being held in spaced relation to each

other by means of the glass guard plate interposed therebetween.

Each of the brackets 27 and 28 is also provided with a stop 38 having a portion thereof extending through a slot 39 in its respective bracket and a thumb screw or the like 40, may be used to clamp the stop in adjusted position in the slot 39. The stop members 38 are for the same purpose as the hook-shaped portion 22 of the member 21 shown in Fig. 4, that is, to prevent bodily movement of the base member in one direction. The auxiliary brackets 32 are held in spaced relation to each other by means of the cross bar 41 fastened by suitable nuts 42 to the brackets 32. The brackets 32 are attached to the brackets 27 and 28, respectively, by means of the screws 43. As will be obvious from an inspection of Fig. 6, the supporting structure 44 is narrower than the base of the machine and the machine overhangs the structure. This arrangement is often found to be desirable with large machines and the use of a machine with such a supporting structure is rendered possible because of the guard plate 35 and the stops 38. If it were not for these last-mentioned attachments to the machine, it would be necessary to have a supporting structure which would extend under substantially the entire machine and even project therebeyond in order to properly safe-guard customers who are apt to be struck by the carriage and its associated parts.

While I have illustrated the brackets which support the guard member as being separate members, it will, of course, be readily understood that the brackets may be made integral with the base member, if desired. Also, similar guard plates may be used to protect the sides of the machine and the opposite end thereof if the same can be done without inconvenience to the operator. Furthermore, it is not necessary that the guard plate be attached directly to the machine, it only being necessary to support the guard plate in a position to protect the customer from the moving parts thereof, as will be readily understood. For instance, the brackets may be supported directly on the counter or other supporting structure, which is adapted to support the slicing machine.

Obviously, those skilled in the art may make various changes in the details and arrangement of parts without departing from the spirit and scope of the invention as defined by the claims hereto appended, and I therefore do not wish to be restricted to the precise construction herein disclosed.

Having thus fully disclosed an embodiment of my invention, what I claim and desire to secure by Letters Patent of the United States is:—

1. A slicing machine comprising a base

member, a carriage adapted to reciprocate on said base member, a bracket adjacent the underside of the base member, opposed openings in said base member and bracket, a foot member engaging said openings, said bracket member having additional means for engaging a fixed part on said base member, and a guard plate supported on said bracket member. 70

2. A device as claimed in claim 1 in which said bracket member has an adjustable stop thereon for preventing movement of said base member and bracket member in one direction. 75

3. In a slicing machine, the combination with a base member, of a carriage adapted to reciprocate thereon, brackets fixed relatively to said base member, an upstanding clamping member rigidly attached to each of said brackets, a second clamping member mounted on each of said brackets movable relative to said first-mentioned clamping member, and a guard plate interposed between the clamping members on each of said brackets. 80 85

4. In a slicing machine, the combination with a base member, of a carriage mounted for reciprocation thereon, brackets, means for holding said brackets in fixed relation to said base member, auxiliary brackets supported on said first-mentioned brackets, each auxiliary bracket carrying a pair of clamping members arranged in opposed relation to each other, a guard plate interposed between opposed clamping members on each of said brackets, and means for drawing said clamping members toward each other. 90 95

5. A device as set forth in claim 4 in which a stop member is provided on one of said first-mentioned brackets for preventing movement of said bracket and base member in one direction. 100 105

6. A slicing machine comprising a base member, a carriage adapted to reciprocate on said base member, feet on said base member, bracket members, recesses in said bracket members in which said feet are adapted to be arranged to constrain said bracket members against upward movement, a second means on said bracket members rigidly engaging portions of said base member for preventing rotative movement of said bracket members relative to said base member, and a guard plate supported on said bracket members outside of the path of travel of said carriage for guarding persons against injury by said carriage when it reciprocates. 110 115 120

7. A slicing machine comprising a base member, a carriage adapted to reciprocate on said base member, a bracket adjacent the underside of said base member, opposed openings in said base member and bracket, a foot member engaging said openings, said bracket member being held in position solely by the weight of said base member, and 125 130

parts supported thereby so as to render said bracket member readily detachable, and a guard plate supported on said bracket member.

5. In testimony whereof I have signed my name to this specification on this 20th day of November A. D. 1929.

HENRY THOMAS.
